Primary Examiner — T. Chase Nelson*Assistant Examiner* — Kathleen M Sims(74) *Attorney, Agent, or Firm* — Knobbe Martens Olson & Bear, LLP(57) **CLAIM**

The ornamental design for a belt, as shown and described.

DESCRIPTION

FIG. 1 is a front perspective view of a belt showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dash-dash broken lines and the broken away symbols in the Figures show portions of the belt which form no part of the claimed design.
